DESIGN FOR A WASHING MACHINE

Andrew H. Gerhardt, Niles Center, Ill., assignor
to Electric Household Utilities Corporation,
Chicago, Ill., a corporation of Illinois

Application February 13, 1941, Serial No. 98,980

Term of patent 14 years

To all whom it may concern:

Be it known that I, Andrew H. Gerhardt, a citizen of the United States, residing at Niles Center, in the county of Cook and State of Illinois, have invented a new, original, and ornamental Design for a Washing Machine, of which the following is a specification, reference being had to the accompanying drawings, forming a part thereof.

In the drawings:

Fig. 1 is a front elevational view of the washing machine showing my new design.

Fig. 2 is a top plan view thereof; and
Figs. 3 and 4 are side and rear elevational views thereof.

I claim:

The ornamental design for a washing machine, substantially as shown.

ANDREW H. GERHARDT.
